UNITED STATES PATENT OFFICE.

JOHN SCHEMINGER, JR., OF PROVIDENCE, RHODE ISLAND, ASSIGNOR TO AETNA AUTOMATIC OIL BURNER, INCORPORATED, OF PROVIDENCE, RHODE ISLAND, A CORPORATION OF NEW YORK.

ROTARY OIL OR HYDROCARBON BURNER.

Application filed May 23, 1925. Serial No. 32,354.

This invention relates to hydrocarbon burners, and more particularly to burners of the type known in the art as centrifugal or rotary oil burners.

5 The main object of the invention is to provide in a rotary oil burner simple and efficient means for introducing fuel oil and steam at the point of delivery to the burner in such manner as to effect a thorough atomization of the oil and the commingling of steam therewith so as to promote combustion and prevent the formation or deposit of carbon within or upon the rotary burner head.

The invention will first be hereinafter 15 more particularly described, with reference to the accompanying drawings, which are to be taken as a part of this specification, and then pointed out in the claims at the end of the description.

20 In said drawings, Fig. 1 is a vertical sectional elevation of a centrifugal or rotary oil burner illustrating a preferred form of embodiment of my invention; some parts of the device being broken away;

25 Fig. 2 is a plan view;

Fig. 3 is a fragmentary detail sectional view on a slightly enlarged scale of the stationary discharge nozzle and parts associated therewith and with the rotary burner head;

30 and

Fig. 4 is a vertical sectional view illustrating a modification of the invention.

Referring to said drawings, in which the same reference letters are used to denote corresponding parts in different views, the letters A and A¹ denote top and bottom plates of the rotary head of a centrifugal liquid fuel burner mounted on a vertical hollow shaft B which extends up through a central opening in the base of the combustion chamber C, which is designed to be arranged within the surrounding walls of a furnace of ordinary construction in a well known manner; said combustion chamber consisting of a body of fire brick or other refractory material supporting a fire ring D; said body being supported upon an underlying curved metallic plate D² having a central circular opening therein with a depending annular flange overlapping and fitting within and resting upon the outer upper edge of a circular trough-like casting E surrounding the shaft B; said casting E having apertured lugs e on its inner circumferential wall with fastening bolts therein for securing it to apertured lugs f projecting from a hollow standard or casting F within which the shaft B has its bearings; said shaft having a gear wheel f¹ thereon in mesh with a gear wheel or worm gear g on a driving shaft G for imparting rotary motion to the burner head. The burner head comprises said top and bottom plates A and A¹, preferably of annular form with substantially concave confronting surfaces, and a subjacent fan wheel A² fixed 65 on the same shaft. Said top plate as shown has a dome-like central portion a with its lower edge surrounding an upstanding flange a¹ on a ring-shaped member overlying and spaced from and secured to the 70 aforesaid bottom plate A¹ which has its central portion a² depressed and supported upon an annular outwardly and upwardly extending flange on the lower end of a hub-like member or sleeve I fixed on the upper end 75 of the hollow shaft B, so as to revolve therewith. An oil feed pipe K extends up through said hollow shaft and carries on its upper end a discharge nozzle L; the lower end of said feed pipe being screwed into a 80 hollow casting M fixed within the lower end of the hollow standard F so as to support the feed pipe stationarily within the hollow shaft B. The delivery nozzle L consists of a substantially semi-globular body having a 85 liquid fuel and vapor receiving and mixing chamber l therein and an apertured bottom plate screwed on the upper end of said feed pipe and formed or provided with a plurality of depending tubular projections each 90 having a discharge tube therein formed with a restricted passage therethrough, preferably a tube of the Venturi type, for discharging jets of commingled oil and steam onto and around the central depressed portion of 95 said bottom plate A¹. The space between the top and bottom plates A and A¹ is gradually enlarged from the peripheral portion thereof toward the center, and the peripheries of the two plates are slightly separated so as to 100 provide a restricted peripheral discharge passage for the gaseous fuel or atomized oil and steam issuing from the burner head through said passage and the periphery of the upper plate extends slightly beyond the 105 periphery of the lower plate so that the gaseous fuel will be discharged in a thin layer or sheet and thrown out horizontally into the

space within the fire ring around the burner head and against the vertical walls of said ring, and as the combustible gases are consumed adjacent to the inner side of said ring and around the top thereof intense heat will be generated within and overlying the fire ring, for heating incoming water and generating steam for admixture with the liquid fuel or fuel oil by means such as I will 10 now proceed to describe.

As shown, a pipe P connected at one end with a water tank or other source of supply (not shown) is coiled around the fire ring D, preferably on the upper outer side thereof, 15 which is recessed to receive and provide a shoulder on which the coil may rest. Said pipe extends downwardly to a coupling member p, for connection with a reduced extension or pipe P¹ of diminutive size which extends through a stuffing box R in a horizontal portion k of the oil feed pipe and along 20 said pipe and upwardly through the vertical portion thereof and terminates within the receiving and mixing chamber of the discharge nozzle so as to introduce steam in 25 said chamber for admixture with the liquid fuel therein at the point of delivery of the liquid, and the steam thus introduced serves to atomize the fuel oil, and the intense heat 30 acting upon the vaporized oil and steam issuing from the discharge nozzle and filling the space between the top of the nozzle and the underside of the top plate A serves to superheat the steam within and issuing from 35 the mixing chamber, whereby any partially atomized oil that may escape is broken up and atomized by the superheated steam with which it is thoroughly commingled and the mixture thus produced is evenly distributed 40 around and within the space encircled by the fire ring so as to insure complete combustion and the generation of intense heat for heating the water pipe surrounding the fire ring and generating steam therein for delivery 45 to the mixing chamber within the discharge nozzle; the rotating burner head being rapidly driven so that the commingled oil-gas and steam is thrown out from between the peripheries of the top and bottom plates there- 50 of at a high velocity in a plane parallel to the flat horizontal peripheral portions of said plates and perpendicular to the fire ring; the speed of rotation being sufficiently high to impart to the outgoing oil-gas and steam 55 a high velocity, which will prevent back firing into the space within the rotating head, and thus prevent the formation and deposit of carbon on the interior of the rotating plates and within the nozzle housed between said 60 plates, also preventing injurious vibration, which results from imperfect atomization of the oil, and consequent return of unburned gases to the interior of the rotating burner head, resulting in the deposit of soot or car- 65 bon therein.

In Fig. 4 of the drawings I have shown a modification in which the chambered discharge nozzle is omitted, and the feed-water pipe P² extends from a source of supply up through the base portion of the fire ring and 70 has a vertical coil P³ formed therein adjacent the inner wall of the fire ring, and from said coil the pipe extends to and through the center of the top plate of the burner head in which is formed an aperture to receive a down-turned end portion of the pipe, which terminates at a point directly above the inlet end of the fuel feed pipe, which enters the space between the top and bottom plates of the burner head underneath said terminal, so that as the liquid fuel issues from the oil feed pipe a jet of steam coming from 80 an opposite direction will be injected into the incoming liquid fuel, with the results hereinbefore stated. 85

The fan underneath the bottom plate of the burner head is similar to that shown in Fig. 1 but it may be of any suitable construction. As shown in Fig. 1 it consists of upper and lower flat rings A² and A³, connected by 90 an annular series of vertically disposed plates or fans α^3 , by the rotation of which air will be driven upwardly around the burner head into and through the film of atomized oil and steam issuing from between the peripheries of the plates A and A¹ of the burner head for supporting and promoting combustion. In Fig. 4 the upper ends of the vanes or fan blades are secured to the lower plate 95 of the burner head instead of being secured to a flat ring A², as in Fig. 1. However, the form of the fan in either case is not essential, as various forms may be used. 100

The vertical shaft to which the burner head is secured may be journaled in ball 105 bearings arranged within the hollow standard F, as shown in Fig. 1, or in any desired manner, but said bearings and the means shown for imparting rotary motion to the burner head may be of the form shown or 110 of any desired construction, and as no claim is made to the shaft bearings or to the means employed for imparting rotary motion to the burner head and parts associated therewith, further description thereof is deemed 115 unnecessary.

In its broader aspects my invention resides essentially in providing simple and efficient means, associated with the feed-pipe and rotating atomizing device of a rotary oil burner 120 or the like, whereby a jet or jets of steam may be injected into the fuel oil as it is delivered to the burner and a thorough atomization of the oil and the admixture of steam therewith effected and a highly inflammable gaseous mixture produced and thrown out by the rotating atomizing device into the combustion chamber, thus promoting combustion and preventing the formation and deposit of soot or carbon on the rotating burner head or atomiz- 125 130

- er. The word "oil" as used herein is intended to include any liquid fuel adapted for admixture with steam, while the word "vapor" applies to vaporized liquid or steam.
5. It will be understood of course that various changes may be made in the details and arrangement of parts without departing from the spirit and scope of my invention, and I therefore do not desire to be limited in the 10 appended claims to the specific form and arrangement of parts shown and described.
- Having thus described my invention, what I claim as new and desire to secure by Letters Patent of the United States is:
15. 1. An atomizing device for rotary oil burners revolubly mounted on a vertical hollow shaft, said device comprising top and bottom plates having substantially concave confronting surfaces and arranged to form a 20 centrally disposed oil and vapor receiving chamber and a restricted peripheral discharge passage in open communication with said chamber, a fuel feed pipe extending up through said hollow shaft having mounted 25 thereon within said chamber a nozzle having depending discharge tubes leading from a fuel and steam mixing chamber therein into said oil and vapor receiving chamber, and means for conducting steam into said mixing 30 chamber at the point of delivery of liquid fuel therein.
2. In a liquid fuel burner, a burner head revolubly mounted on a vertical hollow shaft, a stationary fuel feed pipe within said shaft 35 carrying on its upper end a discharge nozzle centrally arranged between top and bottom plates having their peripheries spaced apart so as to provide a restricted peripheral discharge passage in open communication with 40 a centrally disposed oil and vapor receiving chamber, said nozzle having an oil and vapor mixing chamber therein and said feed pipe extending up through said shaft into said mixing chamber, and means for introducing 45 steam into said mixing chamber for admixture with the liquid fuel therein.
3. The combination, in a rotary oil burner, of an atomizing device including spaced top and bottom plates revolubly mounted on a 50 vertical shaft so as to provide a centrally disposed oil and vapor receiving chamber and a restricted peripheral discharge passage, a fuel feed pipe extending into the space between said plates and carrying a discharge 55 nozzle having a liquid fuel and vapor mixing chamber therein into which the delivery end of said feed pipe protrudes, and means for introducing steam into the liquid fuel as it enters said mixing chamber.
60. 4. The combination, in a rotary oil burner, of an atomizing device including spaced top and bottom plates revolubly mounted on a hollow shaft so as to provide a centrally disposed oil and vapor receiving chamber and a 65 restricted peripheral discharge passage, a fuel feed pipe extending up through said shaft into said chamber and carrying a discharge nozzle having a liquid fuel and vapor mixing chamber therein into which the delivery end of said feed pipe protrudes, and means for introducing steam into the liquid fuel as it enters said mixing chamber.
- fuel feed pipe extending up through said shaft into said chamber and carrying a discharge nozzle having a liquid fuel and vapor mixing chamber therein into which the liquid fuel is discharged, and a pipe within said feed 70 pipe for introducing steam into said mixing chamber.
5. In a rotary oil burner, an atomizing device comprising annular top and bottom plates with opposed concave surfaces revolubly mounted on a vertical shaft so as to provide a centrally disposed oil and vapor receiving chamber and having their peripheries spaced apart so as to provide a restricted peripheral discharge passage in open communication with said chamber, a fuel feed pipe carrying a discharge nozzle centrally arranged between said plates within said chamber and having a liquid fuel and vapor mixing chamber therein into which the liquid fuel is discharged, and means for introducing steam into said mixing chamber for admixture with the liquid fuel therein. 80
6. The combination in a rotary oil burner, of a burner head revolubly mounted on a hollow shaft and having a centrally disposed oil and vapor receiving chamber therein, an oil feed pipe extending up through said shaft, a discharge nozzle fixed on said feed pipe within said chamber and having a fuel receiving and mixing chamber therein into which the liquid fuel is discharged, and a pipe within said feed pipe and associated means for pre-heating water and introducing steam into said mixing chamber. 90
7. In a rotary oil burner, a rotary head having means thereon for distributing liquid fuel by centrifugal force, said head having top and bottom plates with opposed concave surfaces providing an inwardly enlarging oil and vapor receiving chamber in open communication with a restricted peripheral discharge passage and enclosing therebetween a stationary fuel discharge nozzle, said nozzle being of substantially semi-globular form 100 and having a liquid fuel and steam mixing chamber therein, and tubes of the Venturi type for discharging jets of commingled oil and steam into said oil and vapor receiving chamber and means for introducing liquid fuel and steam into said mixing chamber. 105
8. The combination, in a liquid fuel burner, of an atomizing device comprising a revoluble burner head having an oil and vapor receiving chamber therein and a restricted peripheral discharge passage in open communication with said chamber, a liquid fuel and vapor mixing device within said chamber of approximately semi-globular form having a mixing chamber therein and depending tubes of the Venturi type, for discharging jets of commingled oil and steam onto and around the central part of the bottom of said receiving chamber, means for conducting liquid fuel into said mixing device, and means for 115
- 120
- 125
- 130

introducing steam into said mixing device for admixture with the fuel therein.

9. A liquid fuel burner comprising a rotary atomizing device having a centrally disposed liquid fuel and vapor heating and mixing chamber therein and a restricted peripheral discharge passage in open communication with said chamber, a liquid fuel feed pipe protruding into said chamber, a mixing device mounted on said feed pipe, a water supply pipe and means associated therewith for utilizing the heat of the burner to generate steam; the latter pipe terminating within said mixing device in close proximity to and adapted to inject steam into the liquid fuel at the point of delivery thereof into said mixing device, and means for discharging jets of commingled fuel and steam from said mixing device into said heating and mixing chamber, whereby a thorough admixture of the fuel and steam is effected and the mixture vaporized and discharged in a thin film into a combustion chamber.

10. In a liquid fuel burner, a rotary burner head having an oil and vapor receiving chamber therein and a restricted peripheral discharge passage in open communication with said oil and vapor receiving chamber and arranged to discharge commingled vaporized fuel and steam into an encompassing combustion chamber, a fuel and steam mixing device within said receiving chamber, an oil feed pipe protruding into said mixing device, and a steam pipe having its delivery end arranged to discharge into the fuel issuing from said feed pipe at the point of delivery of fuel into said mixing device, for commingling oil and steam, and means for discharging commingled oil and steam from said mixing device into said receiving chamber.

11. In a liquid fuel burner, a rotary atomizing device having a centrally disposed liquid fuel and vapor heating and mixing chamber therein in open communication with a surrounding portion or passage-way which gradually diminishes in size toward its periphery, the peripheral portion thereof forming a restricted discharge passage, a combustion chamber encompassing said device, a liquid fuel feed pipe having its delivery end protruding into said heating and mixing chamber, and means for injecting steam into the liquid fuel at the point of delivery thereof into said heating and mixing chamber, whereby a thorough admixture of the fuel and steam is effected and the mixture vaporized and discharged in a thin film into said combustion chamber.

12. In a liquid fuel burner, a rotary atomizing device of circular form having a centrally disposed and enlarged liquid fuel and vapor heating and mixing chamber therein

in open communication with a surrounding portion or passage-way of gradually diminishing capacity toward its periphery and terminating in a restricted peripheral discharge passage, a combustion chamber encompassing said device, a fuel and steam mixing device within said heating and mixing chamber, a fuel feed pipe protruding into said mixing device, and means for injecting steam into the fuel at the point of delivery thereof into said mixing device, the latter device having means thereon for discharging jets of commingled fuel and steam into said heating and mixing chamber, whereby a thorough admixture of the fuel and steam is effected and the mixture vaporized and discharged in a thin film into said combustion chamber.

13. A liquid fuel burner comprising a rotary shaft carrying an atomizing device having an inwardly enlarging oil and vapor heating and mixing chamber therein and a restricted peripheral discharge passage in open communication with said chamber, a centrally disposed hollow liquid fuel and steam mixing device within said chamber, a fuel feed pipe for conducting liquid fuel into said mixing device, a combustion chamber encompassing said atomizing device, means associated with said combustion chamber for utilizing the heat of the burner to generate steam, and means for discharging the steam into the liquid fuel at the point of delivery thereof into said mixing device; the latter device having depending tubes adapted to discharge jets of commingled oil and steam into said heating and mixing chamber.

14. A liquid fuel burner comprising a rotary burner head composed of substantially circular plates of approximately concavo-convex form secured together with their concave surfaces confronting and their peripheries slightly spaced apart so as to provide a centrally disposed heating and vaporizing chamber which is gradually enlarged toward its center and a restricted peripheral discharge passage in open communication with said chamber, a fuel feed pipe for delivering liquid fuel into said heating and vaporizing chamber, a combustion chamber encompassing said burner head, and a water supply pipe having a part thereof arranged within said combustion chamber and its delivery end protruding into said heating and vaporizing chamber and terminating in close proximity to the delivery end of said feed pipe, whereby the heat of the burner is utilized for heating the water and generating steam for delivery into the liquid fuel in coincidence with and at the point of delivery of the fuel into said heating and vaporizing chamber.

In testimony whereof I affix my signature.
JOHN SCHEMINGER, JR.
